UNITED STATES PATENT OFFICE.

PAUL HANSON, OF WILD HORSE, COLORADO.

BUTTER-MAKING MACHINE.

1,089,836.

Specification of Letters Patent. Patented Mar. 10, 1914.

Application filed June 27, 1912. Serial No. 706,140.

To all whom it may concern:

Be it known that I, PAUL HANSON, a citizen of the United States, residing at Wild Horse, in the county of Cheyenne and State 5 of Colorado, have invented certain new and useful Improvements in Butter-Making Machines, of which the following is a specification.

This invention relates to machines for 10 making butter, and more particularly to large machines of this class which are connected by means of a driving pulley to a suitable source of power.

The principal object, therefore, of the invention is to provide a machine of the class 15 described which is easily controlled and operated and which is effective and efficient in operation.

For the attainment of these ends and the 20 accomplishment of other new and useful objects, as will appear, the invention consists in the features of novelty in the construction, combination and arrangement of the several parts generally shown in the accompanying drawing and described in the specification, but more particularly pointed out 25 in the appended claims.

In the drawings Figure 1 is a view in elevation of the end of a machine showing the 30 operating mechanism applied thereto constructed in accordance with the principles of this invention; Fig. 2 is a side elevation of the machine and mechanism shown in Fig. 1; Fig. 3 is a detail view of one end of 35 the drum or receptacle showing means for tightening the same; Fig. 4 is a sectional view on the line 4—4 of Fig. 1 showing the mechanism for rotating the butter working rollers; Fig. 5 is a detail view partly in section, taken on the line 5—5 of Fig. 1, of the 40 clutch and clutch operating mechanism; Fig. 6 is a sectional view showing the bearing support for one of the butter working rollers at the end opposite the operating 45 end; Fig. 7 is a detail sectional view of the end adjusting means shown by Fig. 3.

In butter working machines of a large size it is difficult not only to mount the rotating drum or receptacle in a suitable manner, but also to provide suitable operating 50 mechanism for rotating the drum. In addition to this, means must be provided for changing the speed not only of the drum itself, but also of the butter working rollers, 55 for the reason that different conditions are

met in churning the cream, and in working the butter after the cream is churned.

The present invention relates more particularly to the manner of moving the drum and the means for operating and controlling 60 the drum and the butter working rollers.

Referring now more particularly to the drawings, the numeral 10 will be employed to designate generally the entire drum or receptacle. This receptacle may be of any 65 suitable diameter and length, machines of various capacities being preferably constructed by varying the length of the receptacle rather than the diameter. To support the receptacle bearing standards 11 and 12 70 are provided, which are located preferably adjacent the ends of the receptacle and are connected to each other by means of the tubular members 13. At the rear end of the receptacle 10 a metal band 14 is disposed 75 and mounted in the bearing standards 11 on opposite sides of the drum are flanged rollers 15 which are disposed so that they contact with the metal band 14 and permit the receptacle to be rotated upon them. At 80 the other end of the receptacle, which will be referred to as the forward end, a metal ring 16 is secured to the receptacle in any desired or suitable manner. This ring is formed on one edge with teeth 17 and on 85 the other edge with a smooth surface 18, which substantially coincides with the pitch line of the gear teeth 17. Mounted in the bearing standard 12 are shafts 19, 19', and mounted upon the shafts are rotatable driving gears 20, 20', having gear teeth 21, and a plain or roller surface 22 substantially coinciding with the pitch line of the gear teeth 21. This driving gear 20 is adapted to mesh 90 with the teeth 17 of the metal ring 16, the roller 22 contacting with the roller surface 18 of the ring to support the receptacle at its forward end. Thus it is seen that the receptacle is suitably mounted for rotation 95 at its ends without the necessity for a central bearing or support or a driving shaft which coincides with the longitudinal axis of the receptacle, and it will be noted that the driving gears at the forward end also support the drum, being formed with a 100 bearing surface which substantially coincides with the pitch lines of the gears and engage with a corresponding surface on the driving ring at the forward end. Disposed about the gear 20 and the gear teeth 17 is a 105

bearing surface which substantially coincides with the pitch lines of the gears and engage with a corresponding surface on the driving ring at the forward end. Disposed about the gear 20 and the gear teeth 17 is a 110

guard 17' which is secured at one end to the bearing standards 12 and at the other end to the tubular member 13. This guard is for the purpose of preventing the engagement 5 of the teeth with the clothing of an operator, and to prevent other materials or substances from lodging in the gears.

To rotate the drum the shaft 19 is provided at its outer end with a driving pulley 23, freely rotatable on the shaft, and with a collar 24 keyed to the shaft. The under surface of the pulley 23 is provided with an inclined face 25, and a clutching member 26 with a correspondingly inclined face is movable longitudinally of the shaft and engages the collar 24 thereof by means of a slot 27. This member 26 is provided with a groove 28 to receive a yoke 29 (see Figs. 1, 2 and 5), which is attached to an operating lever 30. A suitable bracket 31 is provided for supporting the outer end of the shaft 19, and the tubular members 13 are preferably extended in a forward direction to sustain a support 31' which may be connected to or formed integral with the bracket 31, both being adapted to support the outer end of the shaft, and the lever 30 being pivoted to the support 31', as shown, or to the bracket 31. The gear 20 is preferably keyed to a sleeve member 32 (see Fig. 5), which is rotatable upon the shaft 19 and forms a bearing support for the shaft in the bearing standard 12. The gear 20 is also preferably provided with a sprocket portion 33, preferably formed integral therewith, but which of course may be secured to the gear 20 if so desired. The sleeve 32 is formed with a projecting portion 34, which is preferably located on the side of the bearing standard 12 opposite to that of the gear 20, so that when the sleeve 32 is in position in the bearing standard 12 and the gear 20 is keyed, it will be held firmly in place against longitudinal movement with respect to the bearing standard 12. Keyed to the shaft 19 adjacent the extending portion 34 of the sleeve member 32 is a gear 35, and disposed between the gear and the bracket 31 is a freely rotatable member 36, which has an externally toothed portion 37 with internal teeth 38 projecting over the gear 35. Secured to the extending portion 34 of the sleeve 32 and rotatably mounted thereon are pinions 39, which mesh with the gear 35 and with the internal teeth 38 of the projecting portion 37. Formed integral with the member 36 is a tubular portion 40 having an opening 41 and an inclined or beveled cam surface or notch 42 at the outer end thereof. The tubular portion projects in the opposite direction from the flanged portion 37, and is adapted to receive a movable pin 43 (see Figs. 1 and 2) which may be moved longitudinally into and out of position to engage the housings 65 of the pinions 39 or lugs 39' formed on the

side of member 36. This member 36 is also provided about its periphery with a plurality of notches 44, which may be engaged to hold the member 36 in fixed position, as hereinafter described.

The movable pin 43 which is mounted in the tubular portion 40 of the member 36 is provided with an enlarged portion 44', which may be secured thereto or formed integral therewith, and which is formed with a cam-shaped projection which is adapted to be received in the rounded notch or groove 42 of the tubular portion 40. This enlarged portion 44' is provided with arms 45 and 46 which extend substantially at right angles to each other, and which are adapted to be engaged to rotate the pin 43 in the opening 41. When the arms 45 or 46 are so engaged the enlarged portion of the pin is caused to ride upon the grooved portion of the tubular member 40 to move the pin longitudinally into or out of engagement with the projection 34 of the sleeve member 32. The outer end of the pin is engaged or supported by a spring pressed clip 47. This clip has a slotted opening to receive the end of the pin, and is secured through a perforation at the other end to the member 36, the clip being bent or offset to provide for the projection of the tubular portion 40. The clip 47 is preferably of resilient material, and in order to provide for further movement of the pin 43 the connection of the clip to the member 36 is made slightly more flexible, as, for example, by means of a threaded pin 48, which extends through the perforation in the end of the clip and a spring 49 mounted upon the pin with a nut 50 to keep it in position and add the proper tension. The tension of the spring upon the clip may be varied by moving the nut 50 upon the threaded portion of the bolt 48, whereupon the clip 47 will be pressed firmly against the end of the pin 43, tending normally to press it inwardly in the tubular portion 40. When the pin 43 is pressed inwardly it is disposed in the path of movement of one of the lugs 39', whereupon the member 36 and the sleeve member 32 will be driven positively with the shaft 19, forming a direct driving connection for the gear 20 with the shaft 19, so that the gear will be driven at the speed of the shaft and in the same direction. This gearing is of the type commonly known as planetary gearing, and in order to effect a slow speed movement of the driving gear 20 in the forward direction, it is necessary only to withdraw the pin 43 from its engagement with the lugs 39' and to lock the member 36 against rotation with respect to the shaft 19. A simple means of accomplishing this result will now be described.

A lever 51 is provided with a laterally extending pin 52, which is adapted to engage either one of the arms 45 or 46 when the

lever is moved about its point of pivotal support. In the present embodiment of the invention this lever 51 is pivotally mounted by means of lugs 52' (see Fig. 5) on the bracket 31. Secured to or formed integral with the lever 51 is a dog 53, which is adapted to engage in the notches 44 in the periphery of the member 36. A spring 54 is also provided, which is secured in any suitable manner to the bracket 31, and which presses against the lever 51 or against the dog 53, tending to press the latter downwardly into engagement with one of the notches 44. It will be evident that when the planetary gearing is being driven at the same speed as the shaft 19, the pin 43 must first be retracted from its position in the tubular portion 40, and for this purpose the arms 46 are made of sufficient length to be engaged by the pin 52 of the lever 51 before the dog 53 engages in one of the notches 44. As soon as one of the arms 45 or 46 is so engaged the pin will be retracted by reason of the cam-surface of the portion 40, and the corresponding beveled portion of the enlargement 44'. When the dog 53 is disengaged from its connection with one of the notches 44 by moving the lever 51 upwardly, one of the arms 45 or 46 will be engaged by the pin 52 to return the pin 43 to its engaging position in connection with the planetary gearing.

In order to hold the lever 51 and the dog 53 releasably in position, they are preferably provided or formed with a cam 53', (see Figs. 1 and 5), having surfaces disposed at an angle to each other, so that the spring 54 will press against one of the surfaces to hold the dog and lever in engaging position, and against the other surface to hold the dog and lever out of engaging position. An abutment 54' is also formed adjacent the pivoted portion which is disposed to engage the bracket 31 to prevent the lever 51 from being turned over too far. It will be evident that the lever is releasably held in either position by the tension of the spring 54 against the cam 53'.

From this description it is evident that the receptacle 15 may be driven in one direction at either high or low speed without varying the speed of the driving pulley, it being necessary only to move the lever 51 to engage or disengage the clutching member 55 from the driving pulley, whereupon the shaft 19 will be rotated and to position the lever 51 to effect the different changes in speed through the gearing above described.

In machines of this class it is customary to provide butter working shelves 55, and one or more butter working rollers 56. If the machine is a large one, it is preferable to employ two or more butter working rollers and the same number of cradles or shelves 55. These shelves may be arranged in any desired

or suitable position with respect to the rollers 56, and in the present exemplification of the invention the shelves are disposed substantially at right angles to the plane of the axes of the rollers and at the side thereof, so that as the receptacle 15 is rotated the material will be lifted by the shelves and directed against the rollers.

The shelves are preferably formed of separate slats which may be separately inserted and removed. Brackets 55' are secured to the ends of the receptacle in any desired manner and the separate slats or strips are each secured to the brackets in any desired or suitable manner, as for example, so by means of screws.

The rollers are preferably rotated in a reverse direction to the direction of position of the receptacle itself, so that the material carried by the shelves 55 will be directed against the rollers and moved by the latter against the shelves. In order to mount the rollers within the receptacle, and to provide for their rotation in the opposite direction, they are provided at the operating end of the receptacle with a plate 57 which is preferably provided with a rectangular or slotted opening 58 in the center thereof. Secured to the receptacle on the outside and at the forward end thereof is a spider 59, to which is secured a shaft 60. The spider is formed with extending arms which are provided with the tubular portions 61 extending through the end of the receptacle and formed on the inside with a beveled inner surface 62 (see Fig. 4). Disposed in the tubular portions 61 are shafts 63 which are provided with shoulders 64 corresponding with the beveled surfaces 62, and each having a rectangular head adapted to fit the opening in the plates 57. Mounted on the projecting ends of the shafts 63 are gears 65, and mounted upon the shaft 60 is an internally geared member 66, which meshes with the gears 65. Also disposed upon the shaft 60 and preferably outside of the member 66 is a sprocket wheel 67. Both the sprocket wheel 67 and the member 66 are freely rotatable on the shaft 60, and in order to effect the rotation of the rollers 56 suitable connections may be made between the members 66 and 67. For this purpose the member 66 is formed with openings 68 therein, which in case the member 66 is formed with spokes, as shown in the present exemplification of the drawing (see Fig. 1), are disposed in the spokes. A tubular portion 69 is formed in connection with the sprocket 67, which is adapted to receive a pin 70. The outer end of the tubular portion 69 is formed with an inclined beveled surface 71, and the pin 70 is provided with an arm 72, by means of which the pin 70 may be rotated. A spring 73 is suitably disposed within the tubular portion 69, tending to press the pin in-

wardly, and the longitudinal position of the pin is varied by rotating it in the tubular portion, whereupon the arm 72 will engage the outer end of the tubular portion and the beveled surface 72 to move the pin 70 outwardly or inwardly. When the pin 70 engages in one of the openings 68 the sprocket 67 is locked in connection with the member 66 and by rotating the sprocket 67 the gears 65 are caused to rotate, thereby rotating the rollers 56 in the corresponding direction. In order to effect the rotation of the sprocket 67 a sprocket chain 74 connects the driving sprocket 33 with the sprocket 67, and it will be noted by referring to Fig. 1 of the drawing that the rotation of the gears 65 will be in the direction opposite to that of the rotation of the receptacle itself. It is obvious that the butter working rollers 56 may or may not be rotated without interfering with the operation of the receptacle itself. At the other end of the rollers 56 they are preferably provided with a bearing support similar to that shown in cross section in Fig. 6. The end of the roller is recessed adjacent the center and provided with a block 75, of any suitable material, which is perforated at the center of the roller to receive the end of a bearing pin 76. A metallic member 77 is preferably disposed at the bottom of the opening in the block 75, and extends into the roller itself, the top forming a bearing plate for the end of the bearing pin 76. This bearing pin 76 is preferably enlarged and threaded at 78 and provided with a head 79 and nut at the outer end. Secured to the end of the receptacle 15 is a threaded plate 80, in which the pin 76 is adjustable, the threaded portion 78 being adapted to fit the threads in the plate 80. By rotating the bearing pin 76 the roller 56 may be pressed longitudinally in the receptacle, and leakage prevented at both ends of the receptacle.

The opening by means of which material is inserted or removed from the receptacle, may extend the full length thereof if desired, but preferably extends only part of the way and comprises a flat opening formed by omitting a segment from a portion of the receptacle. Sills 81 extend longitudinally of the receptacle and are supported by cross pieces 82. These cross pieces extend across the door opening and the sills 81 are disposed above the cross pieces, so that a flat door 83 may be positioned above the sills 81, and may be suitably held in position by the clamping devices 84. It is obvious that in receptacles of considerable length the hoops which extend and hold the receptacle in shape must also pass across the door opening, and for this purpose the cross pieces 82 are preferably disposed substantially in line with hoops 86, which are adapted to hold the receptacle in shape, so

that the hoops may be disposed on top of the cross pieces 82, and below the top of the sills 81. The door 83 is preferably provided with packing 87 (see Fig. 1), disposed about the edge and extending therefrom, composed of any suitable resilient material, such as cork or the like, which is adapted to tightly inclose the door opening when the door 83 is pressed in closed position.

In order to provide for the expansion and contraction of the receptacle, it is necessary to provide an adjustment, not only for the sides of the receptacle, but also for the ends, and particularly is this true of receptacles of considerable size, for the reason that a little variation of each piece of which the receptacle is constructed will result in a large variation of them all taken together. For this purpose one or both ends of the receptacle may be formed as shown in Figs. 2 and 3, in which it will be seen that one of the end pieces 88 is provided with a metal strip 89 having threaded openings therein to receive the bolt 90. The adjacent end piece 91, which is thicker than the end piece 88, is provided with a portion 92 which extends back of the end piece 88 and in close contact therewith to prevent leakage. A metal strip 93 is disposed between the heads of the bolts 90 and the end piece 91 and held in place by screwing the bolts outwardly in the strips 89, thereby pressing the end piece 91 away from the end piece 88 between the end members of the receptacle. In a similar manner plates 94 and 95 are disposed between adjacent side members of the receptacle separated by the head of a threaded bolt 96, which is threaded through a suitable opening in one of the strips. By turning the bolts 96 the adjacent side members may be pressed apart, thereby tightening the side members on the receptacle. Means is also provided for tightening the hoops 86 of the receptacle to hold the receptacle in shape.

A detailed description of the operation of the machine is believed unnecessary, as the operation of the mechanism has already been described. The levers 30 and 51 are employed to control the operation of the clutch and the gearing by means of which the mechanism may be connected to the driving pulley 23, and the gearing position for high or low speed, as desired. When it is desired to rotate the butter working rollers 56 within the drum in a direction opposite to the rotation of the drum itself, the pin 70 is moved into engagement with the gear member 66, whereupon the gear 65 will be rotated in the direction opposite to the rotation of the drum.

It will be noticed that both of the butter working rollers are rotated in the same direction when connection is made with the sprocket 67, and this direction of rotation is opposite to that of the rotation of the re-

ceptacle itself. These rollers being located at the inner edge of the shelves as they rotate, cause the butter to be worked against and between the shelves and the rollers, thus 5 efficiently working the butter.

What I claim is:—

1. A butter making machine of the class described, comprising a receptacle having a door opening formed by omitting a segment 10 from the receptacle, sills for the door opening, cross pieces extending over the door opening below the sills, binding hoops for the receptacles extending across the door opening on top of the cross-pieces and below 15 the sills, and a flat door for the opening.

2. In a machine of the class described, the combination with a receptacle substantially round in cross section and having flat ends, of end pieces forming the flat ends, and 20 means to engage the end pieces to tighten the ends.

3. In a machine of the class described, the combination with a receptacle substantially round in cross section and having flat ends, 25 of side pieces to cover the receptacle, and means to engage the side pieces to tighten them upon the receptacle.

4. In a machine of the class described, the combination with a receptacle formed of 30 strip material, of means to tighten the strips of the receptacle comprising metal pieces disposed between adjacent strips, and spaced apart, one of the adjacent strips overlapping the other in the inside of the receptacle, 35 one of the metal pieces being provided with threaded openings, bolts screwed in the openings with their heads disposed between the metal pieces and movable to press the pieces apart.

40 5. In a butter making machine, the combination with a receptacle, of means to mount the receptacle for rotation, comprising rollers disposed at the sides and ends thereof, one of said rollers being provided with a 45 sprocket and means to engage the receptacle to rotate it, butter working rollers rotatable in the receptacle, gears secured to the butter working rollers and disposed outside of the receptacle, a freely rotatable internally 50 geared member meshing with said gears, a sprocket co-axially mounted with said member, releasable means to engage the sprocket with said member, a sprocket chain connected to both of said sprockets and means 55 to rotate the first named sprocket to rotate the receptacle in one direction and to rotate the butter working rollers in the other direction when the said releasable means is in engagement.

60 6. In a butter making machine the combination with a receptacle, of means to mount the receptacle for rotation, butter working rollers independently rotatable in the receptacle, and means to press the rollers longitudinally in the receptacle, com-

prising a perforated block inserted in the end of the roller, a metal plate disposed in said opening and secured in the roller, a threaded member secured to the end of the receptacle, an opening being provided therein, and a bearing pin having a threaded portion to engage in said member, a nut and threaded portion at the outer end and a portion extending into the opening in said block against the metal plate. 70

7. In a butter making machine, the combination with a receptacle, of an integrally toothed ring at one end thereof, rollers to support the receptacle for rotation, one of the rollers being formed with a gear to engage the toothed ring, butter working rollers, releasable means to connect both of the butter working rollers to the geared roller for operation in the direction opposite to the rotation of the receptacle, and means to rotate the said roller to effect the rotation of the butter working rollers and the receptacle. 80

8. In a butter making machine, the combination with a receptacle, of a toothed ring at one end thereof, rollers to support the receptacle for rotation, one of the rollers being formed with a gear to engage the toothed ring, means to mount the last named roller to rotate the receptacle, comprising a bearing support, a sleeve member freely mounted therein to which the said roller is secured, a rotatable shaft upon which the sleeve member is mounted, and means releasably to connect the said member to the shaft. 90

9. In a butter making machine, the combination with a receptacle, of a toothed ring at one end thereof, rollers to support the receptacle for rotation, one of the rollers being formed with a gear to engage the toothed ring, means to mount the last named roller to rotate the receptacle, comprising a bearing support, a sleeve member freely mounted therein to which the said roller is secured, a rotatable shaft upon which the sleeve member is mounted, gearing to connect the said member to the shaft, and means to throw the gearing into and out of engaging position. 105

10. In a butter making machine, the combination with a receptacle, of a toothed ring at one end thereof, rollers to support the receptacle for rotation, one of the rollers being formed with a gear to engage the toothed ring, means to mount the last named roller to rotate the receptacle, comprising a bearing support, a sleeve member mounted therein having an extending projection on one side of the support, the roller being secured to the sleeve member on the other side thereof, a rotatable shaft upon which the sleeve is freely mounted, a gear secured to the shaft, pinions rotatably mounted upon the extending portion of the sleeve and meshing with the gear secured to the shaft, 110 120 125 130

a freely rotatable internally geared member mounted on the shaft and with the teeth in engagement with the pinions, and means to lock the last said member in engagement with the pinions whereby the sleeve member will be rotated with the shaft at the same speed thereof.

11. A butter making machine comprising a receptacle, a toothed ring at one end thereof, rollers to support the receptacle for rotation, one of the rollers being formed with a gear to engage the toothed ring, means to mount the last named roller to rotate the receptacle, comprising a bearing support, a sleeve member mounted therein having an extending projection on one side of the support, the roller being secured to the sleeve member on the other side thereof, a rotatable shaft upon which the sleeve is freely mounted, a gear secured to the shaft, pinions rotatably mounted upon the extending portion of the sleeve and meshing with the gear secured to the shaft, a freely rotatable internally geared member, a freely rotatable internally geared member mounted on the shaft and with the teeth in engagement with the pinions, and means to lock the last said member in fixed position upon the shaft whereby the sleeve member will be rotated in the same direction as the shaft at a decreased speed.

12. A butter making machine comprising a receptacle, a toothed ring at one end thereof, rollers to support the receptacle for rotation, one of the rollers being formed with a gear to engage the toothed ring, means to mount the last named roller to rotate the receptacle, comprising a bearing support, a sleeve member mounted therein having an extending projection on one side of the support, the roller being secured to the sleeve member on the other side thereof, a rotatable shaft upon which the sleeve is freely mounted, a gear secured to the shaft, pinions rotatably mounted upon the extending portion of the sleeve and meshing with the gear secured to the shaft, a freely rotatable internally geared member mounted on the shaft and with the teeth in engagement with the pinions, and a pin movable in the last said member into and out of engagement with the pinions, whereby the said sleeve member will be rotated at the same speed as the shaft or at a different speed.

13. A butter making machine comprising a receptacle, a toothed ring at one end thereof, rollers to support the receptacle for rotation, one of the rollers being formed with a gear to engage the toothed ring, means to mount the last named roller to rotate the receptacle, comprising a bearing support, a sleeve member mounted therein having an extending portion, a shaft freely rotatable in the sleeve member, a gear secured to the shaft and disposed in proximity to the ex-

tending portion of the sleeve member, pinions mounted upon said extending portion and meshing with the gear, an internally toothed member mounted upon the shaft having its teeth in engagement with the said pinions, said member being formed with a perforated portion having an edge with a rounded notch therein, a pin movable in said perforation having an outer enlarged portion to engage the notch of said tubular portion, and arms secured thereto by means of which the pin may be rotated and moved longitudinally in said tubular portion into and out of the path of movement of said pinions, the sleeve member being rotated at the speed of the shaft when the pin is in such engaging position.

14. A butter making machine comprising a receptacle, a toothed ring at one end thereof, rollers to support the receptacle for rotation, one of the rollers being formed with a gear to engage the toothed ring, means to mount the last named roller to rotate the receptacle, comprising a bearing support, a sleeve member mounted therein having an extending portion, a shaft freely rotatable in the sleeve member, a gear secured to the shaft and disposed in proximity to the extending portion of the sleeve member, pinions mounted upon said extending portion and meshing with the gear, an internally toothed member mounted upon the shaft having its teeth in engagement with the said pinions, said member being formed with a perforated portion having an edge with a rounded notch therein, a pin movable in said perforation having an outer enlarged portion to engage the notch of said tubular portion, and arms secured thereto by means of which the pin may be rotated and moved longitudinally in said tubular portion into and out of the path of movement of said pinions, the sleeve member being rotated at the speed of the shaft when the pin is in such engaging position, and means to engage the arms to move the pin into and out of engaging position.

15. A butter making machine comprising a receptacle, a toothed ring at one end thereof, rollers to support the receptacle for rotation, one of the rollers being formed with a gear to engage the toothed ring, means to mount the last named roller to rotate the receptacle, comprising a bearing support, a sleeve member having pinions connected thereto and to which the said roller is secured, a shaft freely rotatable within the sleeve member, a gear secured to the shaft meshing with said pinions, an internally toothed member meshing with the pinions and having notched in the periphery, a pin movable through said member into and out of the path of movement of said pinions, means tending normally to press the pin into said engaging position, a lever movable

to operate the pin, and means to engage the notches in the periphery of the said member.

16. A butter making machine comprising a receptacle, a toothed ring at one end thereof, rollers to support the receptacle for rotation, one of the rollers being formed with a gear to engage the toothed ring, means to mount the last named roller to rotate the receptacle, comprising a bearing support, a sleeve member mounted in the support to which the roller is secured, a shaft disposed within the sleeve and freely rotatable with respect thereto, a gear secured to the shaft, means to connect the gear with the sleeve for fast or slow speed in the same direction, a power pulley freely rotatable upon the shaft, a clutching device secured to the shaft and movable into engagement with the pulley, and a lever to operate said clutching device whereby the shaft may be rotated at the same speed as the pulley.

15 mounted upon the shaft having an extending internally toothed portion meshing with the gears, a tubular extending member with a grooved outer edge and a notched periphery, a pin movable in said tubular portion having a cam surface to engage the grooved edge thereof and extending arms, a spring pressed clip bearing against the outer end of the said pin and secured to the last named member, and a lever having a projection

20 to engage the arms of the movable pin, and a dog to engage the notched periphery of the member, the said projection engaging the arms of the pin to withdraw the pin in the tubular portion before the dog engages

25 the notches in the periphery.

17. A butter making machine comprising a receptacle, a toothed ring at one end thereof, rollers to support the receptacle for rotation, one of the rollers being formed with a gear to engage the toothed ring, means to mount the last named roller to rotate the receptacle, comprising a bearing support, a sleeve member having pinions connected thereto and to which the said roller is secured, a shaft freely rotatable within the sleeve member, a gear secured to the shaft meshing with said pinions, a member freely mounted upon the shaft having an extending internally toothed portion meshing with the gears, a tubular extending member with a grooved outer edge and a notched periphery, a pin movable in said tubular portion having a cam surface to engage the grooved edge thereof, and extending arms, a spring

40 pressed clip bearing against the outer end of said pin and secured to the last named member, a lever having a projection to engage the arms of the movable pin, a dog to engage the notched periphery of the member, the said projection engaging the arms of the pin to withdraw the pin in the tubular portion before the dog engages the notches in the periphery, and a spring tending normally to press the lever so that the dog will

45 be in engagement with the notches in said member.

18. In a butter making machine, the combination with a receptacle, of a toothed ring at one end thereof, rollers to support the receptacle for rotation, one of the rollers

being formed with a gear to engage the toothed ring, means to mount the last named roller to rotate the receptacle, comprising a bearing support, a sleeve member mounted in the support to which the roller is secured, a shaft disposed within the sleeve and freely rotatable with respect thereto, a gear secured to the shaft, means to connect the gear with the sleeve for fast or slow speed in the same direction, a power pulley freely rotatable upon the shaft, a clutching device secured to the shaft and movable into engagement with the pulley, and a lever to operate said clutching device whereby the shaft may be rotated at the same speed as the pulley.

19. In a butter making machine, the combination with a closed receptacle rotatable about a horizontal axis, of butter working rollers freely rotatable therein, means without the receptacle to rotate the rollers, comprising a sprocket, rollers to support the receptacle for rotation, one of said rollers being provided with a sprocket formed integral therewith, a chain directly connecting the sprockets, and means to rotate the last named roller whereby the receptacle and the butter making rollers may be rotated.

20. In a butter making machine, the combination with a receptacle, of butter working rollers freely rotatable therein, means without the receptacle to rotate the rollers, comprising a sprocket, a toothed ring secured to the receptacle at one end, rollers to support the receptacle, one of the rollers being formed with a gear and a sprocket integral therewith, a chain connecting the sprockets, the gear of the roller meshing with the toothed ring of the receptacle, and means to rotate the said roller whereby the receptacle and the butter working rollers will be rotated.

21. In a butter making machine, the combination with a receptacle, of means to rotate the receptacle, butter making rollers freely rotatable in the receptacle, and means to rotate both of the rollers in the same direction and opposite to the direction of rotation of the receptacle.

22. In a butter making machine, the combination with a receptacle, of means to rotate the receptacle, and butter working shelves disposed in the receptacle and supported by brackets at the ends, the said shelves comprising slats spaced apart and separately and removably secured to the brackets, the butter material being carried upwardly by the shelves as the receptacle is rotated.

23. In a butter making machine, the combination with a receptacle, of means to rotate the receptacle, butter working shelves disposed in the receptacle substantially at right angles to a diameter thereof and supported by brackets at the ends, butter work-

ing rollers with axes in said diametrical plane and disposed to receive material from said shelves when the receptacle is rotated, and means to rotate both of the rollers in the same direction and opposite in direction to the rotation of the receptacle.

In testimony whereof I have signed my

name to this specification, in the presence of two subscribing witnesses, on this 24th day of June A. D. 1912.

PAUL HANSON.
